US0D1111916S

(12) **United States Design Patent** (10) **Patent No.:** **US D1,111,916 S**
(45) **Date of Patent:** **** Feb. 10, 2026**

(54) **MOTOR VEHICLE, TOY AND/OR REPLICA**

(71) Applicant: **Dr. Ing. h.c. F. Porsche
Aktiengesellschaft**, Stuttgart (DE)

(72) Inventor: **Emiel Burki**, Stuttgart (DE)

(73) Assignee: **Dr. Ing. h.c. F. Porsche
Aktiengesellschaft Germany** (DE)

(**) Term: **15 Years**

(21) Appl. No.: **29/915,728**

(22) Filed: **Nov. 3, 2023**

(30) **Foreign Application Priority Data**

May 5, 2023 (EM) 015020634-0001
May 5, 2023 (EM) 015020634-0006
May 5, 2023 (EM) 015020634-0008

(51) **LOC (15) Cl.** **12-08**

(52) **U.S. Cl.** **USPC D12/86**

(58) **Field of Classification Search**

USPC D12/86, 88, 90, 91, 92, 184, 196;
D21/433, 434, 533, 548

(57) **CLAIM**

The ornamental design for a motor vehicle, toy and/or replica as shown and described.

DESCRIPTION

FIG. 1 is a perspective view of a motor vehicle, toy and/or replica according to a first embodiment showing my new design;

FIG. 2 is a front view thereof;

FIG. 3 is a rear view thereof;

FIG. 4 is a left view thereof, the right side being a mirror image thereof; and

FIG. 5 is a top view thereof.

FIG. 6 is a perspective view of a motor vehicle, toy and/or replica according to a second embodiment showing my new design;

FIG. 7 is a front view thereof;

FIG. 8 is a rear view thereof;

FIG. 9 is a left view thereof, the right side being a mirror image thereof; and,

FIG. 10 is a top view thereof.

The broken lines illustrate portions of the motor vehicle, toy, and/or replica that form no part of the claimed design.

1 Claim, 10 Drawing Sheets
